STUBBING DEVICE

Thorvald F. Hammer, Branford, Conn., assignor
to Malleable Iron Fittings Company, Bran-
ford, Conn., a corporation of Connecticut

Application June 10, 1933, Serial No. 675,172
Renewed March 27, 1935

11 Claims. (Cl. 20—99)

This invention relates to stubbing devices, and more particularly to devices for securing together two adjacent poles, or securing the base of one pole to a stub pole, as is sometimes necessary.

5 After the poles of telephone lines or electric light lines, or the like, have been in the ground for a period of time, they are subject to decay at or below the ground line and become quite weak at this point. It is either necessary to re-

10 move the pole and install a new one or in some way provide means for making the base of the pole secure. If the pole is removed and a new one installed, it means, of course, that the wires, cross arms, etc., must all be removed from the old pole and placed on the new one so that aside from the necessary new equipment, a considerable amount of labor is involved.

15 It has been found satisfactory in many instances to avoid replacing the pole with a new one by inserting a stub pole or short pole into the ground adjacent the old one which has become decayed, leaving several feet of the stub pole projecting above the ground line. The old pole is then secured to the projecting portion of 20 the stub pole by passing straps or bands around both and securing them as tightly together as possible. It is, of course, desirable that the means for securing the poles together be so arranged that the old pole will be secured rigidly and 25 firmly to the stub, and to this end it is advantageous to provide means for drawing the straps or bands tightly about the poles after they have been mounted thereon.

30 It is also desirable to so connect the parts of the securing means that there will be no relative slippage or movement between such parts and no tendency of one part to roll or slide on the other.

35 One object of my invention is the provision of a new and improved stubbing device or means for securing adjacent poles together, such that the device may be readily and easily secured in place and serve to bind the two poles rigidly and securely together.

40 Another object of the invention is the provision of a stubbing or pole-securing device having provision whereby the straps or bands which embrace the pole may be tightened or drawn together by bolts passing between the poles, the

45 bolt-securing devices being so arranged that there will be no possibility of movement between them and the pole-embracing straps.

50 A still further object of the invention is the provision of a pole-securing or stubbing device which will be positive and efficient in operation

and at the same time may be economically manufactured and readily installed in place.

To these and other ends the invention consists in the novel features and combinations of parts to be hereinafter described and claimed.

In the drawings:

Fig. 1 is a side elevational view of a pole and stub pole having my improved stubbing device installed thereon;

Fig. 2 is a sectional view on line 2—2 of Fig. 1;

Fig. 3 is a view similar to Fig. 2 after the bands or straps have been drawn in closely to the poles;

Fig. 4 is a sectional view on line 4—4 of Fig. 3;

Fig. 5 is a sectional view on line 5—5 of Fig. 4;

Fig. 6 is a front elevational view of the clamp casting;

Fig. 7 is a sectional view through this casting on line 7—7 of Fig. 6;

Fig. 8 shows top plan and rear elevational views of the bolt washer; and

Fig. 9 is a view similar to Fig. 1 but showing a modified form of my device.

To illustrate preferred embodiments of my invention, I have shown in Fig. 1 a pole 10 which has been cut off at 11 adjacent the ground line 12 and secured to a stub pole 13 installed closely adjacent the pole 10 and projecting several feet above the ground in a position substantially parallel to the pole 10.

It will be noted that two pole-securing or stubbing devices are shown to secure the poles 10 and 13 together, one adjacent the ground line and the other adjacent the upper end of the stub pole. It will, of course, be understood that as many of these devices as is desired or as is necessary to secure a firm connection may be used. As the two devices shown in Fig. 1 are identical, a detailed description of one will suffice for both.

A U-shaped strap 14 is passed around one pole in an embracing relation, the ends 15 of this strap being sufficiently long to project over the adjacent pole. In like manner, a similar strap 16 embraces the pole 13, the ends of which project over the pole 10. In the form shown in Fig. 1, these straps will be slightly spaced vertically on the poles and will have their ends passed through and secured in castings or brackets 17 positioned opposite each other at the front and rear of the poles.

This casting 17 is shown more particularly in Figs. 4, 6 and 7. It comprises a plate-like structure, shown in Fig. 6, having upper and lower wedge-shaped lugs 18 and 19 projecting rearwardly from the face and designed to enter the space between the poles. Rearwardly of the

front face are provided a pair of transverse slots 20 and 21 which slidably receive the ends of the straps or bands 14 and 16. Adjacent the center of the casting is an opening 22 extending there- 5 through to permit the passage of the bolt 23. It will be understood that the ends of this bolt are passed through the castings on opposite sides of the poles so that by drawing up upon the nuts 24 the castings may be drawn toward each other 10 and the bands drawn closely about and tightened upon the poles.

A slot or opening of keyhole shape 25 is formed in the front face of the casting, and this slot not only communicates with the opening 22 but also communicates at its upper and lower ends with the slots 20 and 21, as shown more particularly in Figs. 4 and 6. The central portion of the opening 25 is somewhat enlarged, as shown at 26, to permit passage of the bolt 23.

20 A washer 27, shown more particularly in Fig. 8, is provided upon each end of the bolt 23. This washer has a substantially flat head provided with a central opening 28 for the passage of the bolt. It is also provided with a pair of rear- 25 wardly projecting lugs 29 and 30 which, when the washer is installed, lie above and below the bolt, respectively, and pass through the upper and lower ends of the keyhole slot 25. These lugs are tapered inwardly, as shown in Figs. 4 and 8, and 30 are provided on their outside surfaces with relatively sharp outwardly projecting ribs 31 and 32.

When this washer is placed upon the bolt 23, the latter is received between these lugs, and the head of the washer may be struck with a hammer 35 to drive it in place. The ends of the lugs 29 and 30 pass into the opening 22 of the casting 17, and the ribs 31 and 32 will be caused to bite into the lower and upper edges of the straps 16 and 14, respectively. This hammering of the washer 40 may be done before the bolt 23 is inserted there- through. The ribs on the washer lugs will, by biting into the straps, interlock with the straps and hence prevent any slipping of the latter through the slots of the casting 17. In other 45 words, the straps will thereby be locked to the casting, and when the nuts 24 are tightened upon the bolt 23, the straps will be caused to bind about and closely embrace the respective poles.

Also, as the bolt 23 is locked within the cast- 50 ings 17, and as these castings are secured to the straps, there will be no tendency when the nuts are taken up upon the bolt 23 for the latter to twist or move, but on the other hand the entire assembly will be held rigidly in position.

55 It will be understood that the lugs 18 and 19 will fit in between the two poles and resist any tendency that the casting might have to roll or move about the surface of the poles. As the nuts are tightened and the straps drawn inwardly 60 from the position shown in Fig. 2 to that shown in Fig. 3, the tension of the straps 16 and 14 will tend to act as a couple pulling the upper end of the casting 17 in one direction and the lower end in the other direction. This will be resisted by 65 the lugs 18 and 19 and also by the contact of the straps themselves within the slots 20 and 21, the fit of the straps within these slots being sufficiently close to prevent any angular movement of the strap therein.

70 Openings 33 and 34 may be provided in the ends of the straps, through which lags may be driven into the poles to secure the ends of the straps tightly thereagainst.

75 In Fig. 9 I have shown a slightly modified form

of my invention. In this form the castings 17a are substantially like the casting 17 heretofore described, except that the slots for the passage of the straps will be slightly deeper so as to permit the ends of two straps to be passed through each of the slots in superposed position instead of one strap, as shown in Figs. 1 to 8. In this instance a U-shaped strap 35 will be passed about one pole, and a U-shaped strap 36 will be passed about the other pole at the same 10 level, the ends of these straps overlapping each other and passing through the same slot in the casting 17a in superposed position. A similar pair of straps will be mounted below those just described to be passed through the other slot of 15 the casting 17a. In other words, in this form of my invention four straps will be employed in each connection instead of two, as shown in Fig. 1. In other respects this form of my invention is like that described in connection with 20 Figs. 1 to 8.

While I have shown and described a preferred embodiment of my invention, it will be understood that it is not to be limited to all of the details shown, but is capable of modification and variation within the spirit of the invention and within the scope of the appended claims.

What I claim is:

1. In a device for securing together a pair of adjacent poles, means embracing said poles, members positioned on opposite sides of the poles through which said embracing means pass, means to draw said members together to bind the embracing means about the poles, and wedge means supported by said drawing means to secure said members to the embracing means to prevent relative movement therebetween. 30

2. In a device for securing together a pair of adjacent poles, strap-like means embracing the poles, members positioned on opposite sides of 40 the poles and having slots through which the strap-like means pass, means cooperating with the walls of the slot to bind said strap-like members against slippage and a bolt passing between the poles and connected to said members to draw 45 them together.

3. In a device for securing together a pair of adjacent poles, strap-like means embracing the poles, bracket members positioned on opposite sides of the poles and having slots through which the strap-like means pass, a bolt passing between 50 the poles and connected to said members to draw them together, and wedge members to secure said strap-like means against movement relatively to said bracket members. 55

4. In a device for securing together a pair of adjacent poles, strap-like means embracing the poles, bracket members positioned on opposite sides of the poles and having slots through which the strap-like means pass, a bolt passing between 60 the poles and connected to said members to draw them together, and wedge members upon said bolt to secure said strap-like means against movement relatively to said bracket members.

5. In a device for securing together a pair of adjacent poles, a pair of bracket members adapted to be disposed in the space between said poles on opposite sides thereof, said members being provided with slots therein, a strap-like member embracing one of said poles and having its ends received in certain of said slots, a second strap-like member embracing the other pole and having its ends received in certain of said slots, wedge members securing the ends of said strap-like members against movement in the slots, and 70 75

means to draw said bracket members together to cause said strap-like members to embrace the poles closely.

6. In a device for securing together a pair of adjacent poles, a pair of members adapted to be disposed in the space between said poles on opposite sides thereof, said members being provided with slots therein, one of the slots in said members being above that of the other, a strap-like member embracing one pole and passing through the upper of said slots, a strap-like member embracing the other pole and passing through the lower of said slots, elements positioned between said strap-like members and securing the latter to said first-named members, and means to draw said strap-like members together to cause them to tightly engage the poles.

7. In a device for securing together a pair of adjacent poles, a pair of members adapted to be disposed in the space between said poles on opposite sides thereof, said members being provided with slots therein, one of the slots in said members being above that of the other, a strap-like member embracing one pole and passing through the upper of said slots, a strap-like member embracing the other pole and passing through the lower of said slots, elements positioned between said strap-like members and securing the latter to said first-named members, means to draw said strap-like members together to cause them to tightly engage the poles, and rearwardly projecting means on said first-named members to engage the rounded portions of the poles.

8. In a device for securing together a pair of adjacent poles, a pair of members adapted to be disposed in the space between said poles on opposite sides thereof, said members being provided with slots therein, strap-like members em-

bracing the poles and having their ends received in said slots, a bolt passing through said slotted members to draw them together to bind the strap-like members to the poles, and washers positioned about said bolts and engaged with said strap-like members and said first-named members to secure them together.

9. In a stubbing device for securing together a pair of adjacent poles, means for embracing the poles, brackets on opposite sides of the poles having openings into which the ends of the embracing means are inserted, wedge-like members secured to the bracket and engaged with said embracing means to secure the latter to the brackets, and means engaging said brackets to draw them into the spaces between the poles.

10. In a device for securing together a pair of adjacent poles, an embracing member embracing each of the poles, a bracket member upon each side of the poles, the ends of said embracing members being received in said brackets in spaced relation, means disposed between the ends of the embracing members to wedge them into firm contact with the brackets, and means disposed between the embracing members and engaging the brackets to draw the latter toward the poles.

11. In a device for securing together a pair of adjacent poles, an embracing member embracing each of the poles, a bracket member upon each side of the poles, the ends of said embracing members being received in said bracket in spaced relation, and a wedge-like member insertable in an opening in the bracket member between said embracing members and in a direction transverse thereto and having ridges thereon to bite into said embracing members to secure them to the corresponding bracket.

THORVALD F. HAMMER.
